UNITED STATES PATENT OFFICE.

JOSEPH PRESCOTT, OF ST. BONIFACE, MANITOBA, CANADA.

SELF-CLEANING SPARK-PLUG.

1,175,176.

Specification of Letters Patent. Patented Mar. 14, 1916.

Application filed April 20, 1915. Serial No. 22,660.

To all whom it may concern:

Be it known that I, JOSEPH PRESCOTT, a subject of the King of Great Britain, residing at St. Boniface, in the Province of 5 Manitoba and Dominion of Canada, have invented new and useful Improvements in Self-Cleaning Spark-Plugs, of which the following is a specification.

This invention relates to spark plugs or 10 igniters for internal combustion engines and the principal object of the invention is to provide a plug constructed in such a manner that its electrodes cannot become fouled by carbon.

15 Another object of the invention is the provision of a self-cleaning plug of this character which is so constructed that the gases have a full sweep through and across the contacts and whereby the ionized air produced by the static spark preceding the arc 20 may form a vehicle for the support of the current across any of the terminals or electrodes.

Another object of the invention is the 25 provision of a plug having one of its electrodes formed from a plurality of converging wires arranged to produce a cage in which is supported an intermediate electrode whose mobility acts to clean the several wires forming the cage electrode.

30 Further objects of the invention will appear as the following specific description is read in connection with the accompanying drawings which form a part of the application and in which:—

Figure 1 is a side elevation, Fig. 2 is a longitudinal section therethrough, and Fig. 3 is a bottom plan view.

Referring more particularly to the drawings 40 1 indicates the metallic body which is as usual provided with the external screw threads 2 for adapting the plug to the engine cylinder. The body 1 is provided with a central bore to its upper end then at 45 its lower end to produce a shoulder 3 against which the external shoulder on the porcelain insulating member is adapted to rest. The insulating member with its associated contact 5 is held within the body 1 50 by means of the clamping nut 6.

All of the foregoing description relates to the present type of spark plug now in common use.

Depending from the lower end of the body 1 are a plurality of fingers 8 and 9 55 the former of which have their ends bent inwardly so that all of the fingers 8 converge toward a common point and have their ends in contact as shown in Fig. 3. The fingers 9 alternate with and secure the 60 spaces between the fingers 8 and are approximately one-half as long, terminating in points 10. All of the fingers 8 and 9 when thus arranged produce a cage through which the gases may freely pass in any direction and arranged within the cage which is generally indicated at 11, is a movable metallic member 12 which forms an intermediate electrode and is constantly interposed between electrode 5 and electrode 11. 70 This member 12 is readily moved around by the action of the moving gases within the cylinder and thereby keeps itself and the electrodes 5 and 11 free of carbon or other deposits which affect proper ignition. 75 As it will be readily seen that the gases within the cylinder may pass through the cage from any direction, the ionized air produced by the spark plug preceding the arc may be blown in any direction according 80 to the movement of the gases within the cylinder and thereby increase the size or fatness of the spark.

This type of cage electrode has many advantages over a slotted cage electrode, as 85 in the latter instance the gases can only travel through this electrode when diametrically opposite slots are alined with the line of travel of the gases.

What is claimed is:—

In a device of the kind described in combination, a metallic body having external screw threads, said metallic body being hollow, a cage mounted upon said body and consisting of a plurality of arcuate fingers having their inner ends secured upon the periphery of said body and disposed as a radial series with their outer ends forming points adapted to contact in a circle, a second series of fingers having their inner ends secured upon the periphery of said body and terminating substantially short of the contacting points of said first named fingers, said second series of fingers having points, said points being curved around and pointing toward the point of contact of said

first mentioned fingers, a contact member disposed centrally in said hollow body and projecting into said cage, and a ball adapted to contact with any point of the length of 5 said first or second named fingers and to extend into said hollow body in contacting relation with said contact member.

In testimony whereof I affix my signature in presence of two witnesses.

JOSEPH PRESCOTT.
